UNITED STATES PATENT OFFICE.

LOUIS FLICKER, OF LOS ANGELES, CALIFORNIA.

HAT-BLOCKING APPARATUS.

No. 896,370.

Specification of Letters Patent.

Patented Aug. 18, 1908.

Application filed September 23, 1907. Serial No. 394,060.

To all whom it may concern:

Be it known that I, LOUIS FLICKER, a citizen of the United States, residing at Los Angeles, county of Los Angeles, State of California, have invented new and useful Improvements in Hat-Blocking Apparatus, of which the following is a specification.

Heretofore in the renewing of worn out and broken hats the whole hat, including the 10 brim, has been softened by heating and by steaming so that the brim had to be re-shaped to the wearer's head. In the majority of cases it is not necessary or desirable to re-shape the brim as it is usually the 15 crown which becomes worn out.

The object of my invention is to provide a device with which the crown of a hat may be heated and steamed without softening the 20 brim thereof so that the crown may be re-blocked without the necessity of re-shaping the brim to fit the wearer's head.

A further object is to provide means whereby the steam which comes in contact with the crown is rendered dry so that the 25 crown does not become permeated with moisture.

I accomplish these objects by means of the device described herein and illustrated in the accompanying drawings in which:—

30 Figure 1,—is a sectional elevation of my improved apparatus. Fig. 2,—is an enlarged detail section of the hat steaming receptacle. Fig. 3,—is a plan view of the same with the inner fabric lining removed.

35 Referring to the drawings 5 designates a steam boiler preferably supported on a stand or legs 6 and adapted to be heated by a gas burner 7 controlled by valve 8. Boiler 5 is provided with a water-gage 9 and a blow off 40 10 of usual construction. A spraying nozzle 11 is provided which is similar in construction and operation to the one described in my Patent No. 856,458, dated June 11, 1907, and entitled Steam generator for setting,

45 shaping and renovating hats. Boiler 5 is further provided with an elliptical top 12 on which the work of re-shaping the brims of hats is performed and for heating the same prior to and during the reshaping operation.

50 On the side of boiler 5 opposite sprayer 11 is a hat steaming receptacle 13 preferably oval in plan which is connected by pipe 14 to boiler 5, the passage of steam therethrough being controlled by valve 15 directly under 55 receptacle 13. The receptacle is provided with a conical bottom 16 into the center of

which pipe 17 leading from valve 15 is placed, the pipe being provided with a U shaped fitting 18 which is adapted to turn the emerging steam downwardly so as not to impinge 60 directly upon hat 19, shown in dotted lines in Fig. 1, the receptacle being large enough to receive the largest sized hat. A drain pipe 20 is provided for the escape of condensed steam from the receptacle so that the 65 inside of the same is kept full of dry steam at all times. An inner cloth lining 21 is further provided which is adapted to catch condensed particles of steam and allow the same to fall downwardly to the bottom of 70 the receptacle without coming in contact with the hat placed therein. By removing the U shaped fitting the receptacle may be used as a funnel for filling the boiler.

When in position in the receptacle the 75 brim of a hat hangs over the rim of the receptacle as shown in dotted lines in Fig. 1. From this figure it will be noted that the crown of the hat is in a position to be thoroughly heated and steamed by the vapor 80 emerging from inverted U shaped fitting 18, while the brim of the hat is entirely protected from being heated by the same. Thus it will be manifest that the brim will retain its original shape while the crown will be rendered pliable so that the same may be shaped to any desired configuration.

85 From the foregoing description it will be observed that I have provided means whereby the crowns of hats may be thoroughly renovated without the necessity of softening the brims and subsequently re-shaping the same. This is especially desirable in both Panama straw and felt hats as it is usually the crown which becomes broken 95 and un-shaped while the brim remains in good condition.

Having described my invention what I claim as new and desire to secure by Letters Patent is:—

1. In a device of the class described, a steam boiler; an elliptical receptacle connected to said boiler, the top of said receptacle being open; an inner fabric lining for the lateral walls of said receptacle; and a tube 105 adapted to lead off the water of condensation from the receptacle.

2. In a device of the class described, a steam boiler; a spraying nozzle connected with said steam boiler; an elliptical receptacle connected to said boiler, the top of said receptacle being open and adapted to receive

the crown of a hat; an inner fabric lining for said receptacle adapted to lead the condensed steam to the bottom of the same; and a tube adapted to lead the water of condensation from the receptacle.

3. In a device of the class described, a receptacle with an open top adapted to receive the crown of a hat; an inner fabric lining for the side walls of said receptacle; and means to supply steam to said receptacle.

4. In a device of the class described, a receptacle of horizontal elliptical cross-section

with an open top; an inner fabric lining for the elliptical walls of said receptacle; a steam inlet discharging into said receptacle against the bottom thereof; and a drainage outlet in the bottom of said receptacle.

In witness that I claim the foregoing I have hereunto subscribed my name this 13th day of September, 1907.

LOUIS FLICKER.
